UNITED STATES PATENT OFFICE.

GEORGE A. KEHL, OF ST. PAUL, MINNESOTA.

SAND TOY.

1,425,865.

Specification of Letters Patent. Patented Aug. 15, 1922.

Application filed May 2, 1921. Serial No. 465,973.

To all whom it may concern:

Be it known that I, GEORGE A. KEHL, a citizen of the United States, residing at St. Paul, in the county of Ramsey and State of 5 Minnesota, having invented certain new and useful Improvements in Sand Toys, of which the following is a specification.

This invention relates to automatic mechanical toys of the gravity operated type.

10 An object of the invention is to provide a sand operated toy having continuous motion as long as supplied with sand, which will be particularly amusing because of the extensive cycle through which the moving 15 parts are directed, due to the novel, simple construction of the device.

A further object of the invention, is the provision of a gravity actuating toy, which will dump its discharging load outside its 20 own base, so that the utilized sand will be deposited in two distinct widely separated piles, so that it may be conveniently scooped up and placed into the hopper, without mingling with the lower part of the toy 25 structure.

A still further object of the invention is the provision of a reciprocatory lever, carrying symmetrically positioned dumping buckets, which, to lend neatness to the 30 appearance of the device, are round and tapered and which operate in connection with tripping mechanism of novel construction, wherein the loaded pails will impinge upon a triangular tripping lever presenting a 35 wide horizontal edge so as to render the action of the device positive even though the construction thereof is crude and inaccurate, after the manner of toy construction.

A still further object of the invention, is 40 the provision of a device of the class described, wherein the discharge spouts in open communication with the hopper, may be relatively close to each other, so as to be positioned near the lowermost portion 45 of the inwardly inclined walls of the bottom of the hopper, whereby approximately all the sand in the hopper will be utilized before the device is rendered inactive.

Another object of the invention is the 50 provision of a toy, having a supporting frame with four outwardly flaring corner uprights, whereby to increase its base area, the frame being constructed with readily removable cross struts arranged close to 55 the floor, which, when removed, enable the uprights to be swung inwardly so as to be

capable of being packed into a container of parallel width and height, to avoid the cost of making of special irregularly shaped boxes.

To this end, the invention consists in the construction, combination and arrangement of parts hereinafter described and claimed.

In the annexed drawings, forming part of this specification:

Figure 1, is a perspective view of a toy embodying my invention.

Figure 2, is a fragmentary side view showing the bucket supporting beam or lever, mounted on its support, and a portion 70 of the hopper including one of the discharge spouts and its valve.

Figure 3 is a fragmentary side view, drawn to an enlarged scale, of a corner of the hopper partly in section, showing the 75 pivotal upper end connection of one of the four uprights.

Figure 4, is a fragmentary perspective view of the cross-struts, showing the manner of attaching the same to the uprights, 80 and.

Figure 5 is a perspective diagrammatic view showing how the four uprights may be swung into parallelism so as to be packed into a carton of uniform width and height.

In the drawings, A designates an oblong hopper having parallel vertical end walls 1, and side walls 2, said walls being bent inwardly respectively on the bending lines 3 and 4, to form a funnel shaped bottom 5. Extending centrally from the bottom of the hopper to the floor, in vertical position to support the hopper, is the standard or column 6, formed of two relatively wide spaced members of uniform width, to form a space 7 between them. Immediately adjacent the lower extremity of the column, is the rectangular aperture 8, and approximately midway of its length, the column is provided with the horizontally disposed pivot pin 9. The flat sides of the column are in parallelism with the long walls 2 of the hopper and movable in the space 7 between its members and supported pivotally on the pivot pin 9 is the bucket supporting beam 10. To sustain the column 6 and the hopper at the top thereof in vertical position, each corner of the hopper is provided with a downwardly and outwardly extending angle upright 11, the upper end thereof embracing the corner formed by the juncture of the walls 1 and 2, and extending under the downwardly direct-

ed fold 12, extending around the upper edge of the hopper.

To hold the uprights from withdrawing from the fold 12, the upright underlying same and the wall 2 are indented as at 12', preferably from without inwards, as by means of a punch or set whereby the three elements are indented collectively as shown in Figure 3. By this means the upright is anchored and may be swung inwardly to a position at right angles to a position parallel with the column 6.

At their lower extremities, the angle uprights at the juncture of the legs of the angle are pierced by the vertically disposed slot 13, the legs of the angles being bent outwardly to form suitable feet 14. For the purpose of supporting the uprights in inclined position and the column centrally between them, I provide the cross-struts 15, which latter are notched centrally at 16, to form a halved joint.

In the process of assembling these struts the two struts are projected through the aperture 8, in the column 5, in crossed relation, said aperture being of sufficient height to permit the struts to be interlocked therein. The ends of the struts are reduced in width to form a tongue 17, which is projected through the slot 13 and bent laterally to lock it in the upright.

In Fig. 5, is shown diagrammatically, the position of the upright when prepared for packing in cartons adapted to fit closely around same. The swinging feature of the upright, enables the use of boxes of uniform dimensions which cost less than irregular shaped cartons and have the advantage of stacking more economically. By attaching the struts in the manner described any unskilled person may assemble the device without any special tools.

In Figure 1, one of the uprights is shown in dotted lines. Referring now to the beam 10, the ends are bent to form forks 18, the latter being equidistant from the pivot 9, and having supporting pins 19, parallel with the pivot 9, whereon are swingingly supported the buckets 20. The buckets are pivoted adjacent their upper edges and at their diameters so as to swing freely on said pin. As shown, the beam 10 is crooked in the center at the pivot 9, so as to bring the supporting beam 19 at its opposite ends, a distance above the plane of the pivot 9, the purpose of which will be hereinafter explained.

In open communication with the interior of the hopper A, one for each bucket, and extending downwardly and outwardly, are the spouts 21, the mouth 22 of the spout being directly over the bucket, when the fork of the beam is swung to its uppermost position. Extending downwardly from the lower edge of the spout, are the spaced lugs

23, having pivot pin 24 parallel with the pivot 9, and pivotally supporting on said pin, of which the latter is a part, valve mechanism B. This mechanism comprises a V-shaped lever 25 pivoted intermediate the ends of one leg thereof on the pin 24, and having at the outer extremity of said leg, in a plane at right angles to said V-shaped lever, a valve disk 26 adapted to swing upwardly against the spout 21 to close its opening 22 as shown in Figure 1. Suspended from a point at the juncture of the V-shaped lever, as by wire 27, is the counter weight 28, whereby said valve disk is held constantly normally against the spout to hold it closed. The pivot 24, constitutes a fulcrum for the V-shaped lever. The lower leg of the V-shaped lever is formed with a relatively long edge 29 arranged parallel with the pivot 9, said edge being positioned in the path of the bucket to contact with the outer rounded surface thereof, thereby causing the V-shaped lever to swing upon its fulcrum to uncover the mouth of the spout. Suitably attached to the lower edge of the bucket, as by means of the lug 29, and to the beam 10 by means of an opening 30, is the flexible cord 31. This cord is of suitable length to restrict the pivotal swinging movement of the bucket in its downward movement, so that when it has arrived at its lowermost position it will, axially, assume a horizontal position. As the buckets shown in its drawings are tapered, the sand cannot remain therein when in its lowermost position. Obviously as the sand is discharged from the lower bucket the upper loaded bucket will begin to descend, while the counter-weight 28, will seat the valve 26 against the spout, immediately the bucket recedes from the edge 29 of the V-shaped lever.

Thus, the operation is repeated the empty bucket rises in turn, and striking the V-shaped lever to open the opposite discharge spout 21. If, as shown, in dotted lines, in Figure 2 of the drawings, a straight beam were used instead of a bent one, as described, the lower bucket in its dumping movement would discharge its cargo within the rectangle described by the feet of the uprights, thus mingling the sand with the struts 15, and making it more difficult to return it to the hopper. The important advantage, however, of having a bent lever resides in the increased leverage obtained for tripping the valve mechanism B, as is clearly indicated by the dotted lines in Figure 2, the distance a from the perpendicular always being equal, as distinguished from a bent lever as herein employed, wherein the distance b at the lower end of the beam is nearly three times a , thus giving a long leverage on one side of the fulcrum equal almost three to one. This makes the

toy positive in its action inasmuch as there is a large margin of leverage to trip the usually inaccurately built tripping mechanism in devices of this character. By providing a relatively long edge 29 on the tripping lever to be used in connection with round buckets of the shape shown, a considerable amount of side play at the free ends of the beam 10 is permissible, it being very difficult to construct toys with long swinging beams that will operate with accuracy at their outer ends.

I claim:

1. In a sand toy, the combination, a frame, a hopper supported by the frame and having a pair of oppositely disposed downwardly directed discharge openings positioned symmetrically about a vertical axis, separate valve mechanism for each of said openings, said mechanism consisting of a lever formed with a valve, said lever being pivoted adjacent the discharge opening to swing upwardly against said hopper to thereby cover said opening and having an arm extending below its pivot, means constantly tending to swing said lever upwardly, a beam pivoted midway between its ends in said vertical axis below said valve mechanism and having a bucket, one at each end thereof, pivotally mounted, so as to swing in the vertical plane of said discharge openings and against said extending arm to move it, and means connected with said beam for restricting the swinging movement of said buckets.
2. In a mechanical toy, the combination, a supporting frame, a hopper supported thereon having a pair of spaced oppositely disposed downwardly opening discharge spouts, independent valve mechanism for closing each of said spouts, said mechanism comprising, a V-shaped lever formed with a valve, said lever fulcrumed below the spout to swing with its valve against the latter to close it, one leg of the V-shaped lever extending downwardly, a counterweight on the lever opposite said valve, and a vibratory beam, having a bucket swingingly mounted at each end thereof, each bucket having means to restrict its swinging movement, said beam pivoted in a manner midway between its ends at a position below and midway between said spouts, to vibrate in the vertical plane of said spouts and engage al-

ternately with its buckets, when vibrated, respectively said downwardly extending legs, 55 said beam being bent upwardly intermediate its ends for the purpose set forth.

3. In a mechanical toy, the combination, a supporting frame, a hopper supported thereon having a pair of spaced oppositely disposed downwardly opening discharge spouts positioned symmetrically about a vertical axis, independent valve mechanism for each of said spouts, said mechanism comprising a pivotally mounted counterweighted lever, 60 extending over the opening of the spout to close it and having a downwardly extending arm, intermediate its ends, a vibratory beam, having a bucket pivotally mounted at each end thereof, each bucket having a flexible 70 connection with said beam to control its swinging movement, said beam being pivoted midway between its ends below said spouts in said vertical axis, and being adapted when vibrated to bring its buckets alternately into engagement respectively with said downwardly extending arms, and under said discharge openings, the pivots of said buckets being positioned in a plane above 75 the pivot of said beam.

4. In a toy of the class described, a rectangular hopper having a pair of discharge openings in the bottom thereof, an outwardly and downwardly extending supporting upright pivotally secured at each corner of 85 said hopper, each upright having a slot at its base, a vertical column secured to the under side of the hopper and having a transverse aperture adjacent the base thereof, valve opening and closing instrumentalities 90 including a vibratory actuating lever on said hopper for each of said discharge openings, gravity actuatable vibratory receiving and discharging instrumentalities mounted on said column adapted to alternately operatively engage said actuating levers, and a pair of readily removable struts, formed with tongues at their ends and interlocking 95 crossed at right angles and extending through said aperture and with their tongues 100 through the respective slots of said upright, said tongues being capable of being bent laterally by hand to hold the uprights positioned relative to said column.

In testimony whereof I affix my signature. 105
GEORGE A. KEHL.
